UNITED STATES PATENT OFFICE

FRANZ HOUST, OF PILSEN, CZECHOSLOVAKIA

OIL SWITCH WITH ROTATABL CONTACT BRIDGE

Application filed March 3, 1931, Serial No. 519,744, and in Czechoslovakia October 10, 1930.

This invention relates to an improved oil switch with a rotary motion contact bridge, and in particular to a three phase arrangement of the same within a single container.

5 The hitherto known designs of oil switches with a contact bridge rotatably movable on a horizontal plane could only as a rule be employed in connection with single phase oil switches with upright cylindrical tanks. 10 Tanks of this type are also used in other forms of oil switches, mainly for mechanical reasons, although in these cases the space within the tank is not utilized to such good advantage as in the case of the design with 15 a rotatably movable contact bridge.

The construction of three phase oil switches, having all three phases arranged in a single tank and employing rotatable contact bridges, has hitherto been attended with 20 difficulties, particularly in the matter of dimensioning, since it has been necessary to provide such clearance between the single phases that, in the circuit-breaking position, in which the contact bridges are generally at 25 right angles to the plane on which the lead-in bushings of the separate phases are disposed, the contact bridges do not strike against each other; the efforts hitherto made by designers to comply with this requirement have led to unnecessarily large dimensions for the containers. Further, when 30 straight-line contact bridges have been employed, the metallic support for the contact bridge causes the arc over path between the 35 contacts of one phase to be shortened, which is particularly noticeable in the case of medium voltages up to 30 kilovolts, at which voltages the individual lead-in bushings could 40 otherwise be arranged nearer together, in view of the shorter arc over path to be allowed for.

These drawbacks have hitherto prevented the utilization of the advantages to be obtained by the use of rotatably movable contact bridges in connection with voltages under 30 kilovolts, at which voltages it is usual to arrange all three phases within a single container.

50 The present invention enables all the

above-described disadvantages to be obviated, and at the same time a number of constructional improvements in oil switch design to be achieved.

For the purpose of enabling the lead-in bushings to be brought closer together, without danger of collision between the rotatable contact bridges, these latter are disposed, in accordance with the invention, in different planes. The above-mentioned shortening of the arc over path between the contacts of each phase, due to the presence of the metallic supporting element, in the circuit-breaking position is obviated by the employment of suitably arched or curved contact bridges. A further constructional improvement effected by the invention consists in eliminating the special spring heretofore used for the braking of the circuit-breaking movement of the contact bridge, and in the employment for this purpose, in conjunction with appropriate accessory means, of the spring which serves to maintain the contacting pressure between the contact bridge and the contacts of the leads-in.

An example of a three phase oil switch in accordance with the present invention is shown diagrammatically in the accompanying drawing, in which

Fig. 1 is a transverse section of the switch,

Fig. 2 shows the same switch partly in longitudinal section, and partly in side elevation.

Fig. 3 represents the same switch, as seen from above, in part section and part elevation, and

Figs. 4 and 5 show details of the construction on an enlarged scale.

Referring to the drawing the tank employed in accordance with the invention is in the form of a longitudinally disposed cylinder 1 which contains the entire circuit-breaking mechanism. This shape of tank is most suitable from the point of view of power of resistance to internal pressure, as in the case of the existing single phase switches, the space within the tank being at the same time particularly advantageously utilized. The contact bridges 2 of the separate phases are arched in accordance with the invention, so

that the distances between the leads-in of one phase, e. g. between the leads-in 3 and 3', within the tank can be reduced to the lowest limit admissible in view of the voltage employed, without the shortening of this arc over path by the metallic supports 6 of the contact bridges in the circuit-breaking position of the switch. For the purpose of enabling the intermediate distances between the leads-in 3, 4, and 5 of the separate phases to be reduced as far as possible the separate contact bridges are disposed, in accordance with the invention, on different planes, as shown in Fig. 2, so that the contact bridges during the circuit-breaking movement pass over or beneath each other.

It will be clear that, by this arrangement of the component parts, the dimensions of the tank can be kept down to a minimum, while the insulating clearances are utilized to the best possible advantage.

For the purpose of braking the circuit-breaking movement of the contact bridges 2 and of the shafts 7 which are of insulating material the spring 8, which maintains a constant pressure between the contacts 9 and the contact bridges 2, is employed. To the lid of the tank there is attached a member which is provided with a stop 10 the arresting surface 11 of which is suitably inclined in relation to the middle axis of the shaft 7. The shaft support 12, with which the operating rod 13 is adapted to engage, is rigidly connected to the shaft 7, and is provided with a laterally projecting nose 14 which bears on the inclined arresting surface of the stop 10 during the circuit-breaking movement of the switch. In consequence of the angle of inclination of the bearing surface 11 of this stop the spring 8 is compressed, and at the same time a braking action is exerted on the movement of the switch, to an extent which is limited by the width of the clearance 15. The angle of inclination of the stop, that is to say of the bearing surfaces of the stop and of the nose on the shaft support of the actuating shaft 7, as well as the clearance which limits the compression of the spring 8 are such that the whole clearance is occupied upon the engagement

of the nose and the stop, at which point the braking action is completed.

It will be clear that the actual construction of the switch herein described and illustrated is capable of various modifications as to detail, without alteration of or departure from the essential nature of the improvements provided by this invention. It will also be clear that the individual features of the invention can be applied separately, and as such provide advantages over existing current practice, while multiple advantages accrue from the employment of all these features in combination.

I claim:—

1. A polyphase oil switch comprising a tank, a plurality of shafts spaced lengthwise of and depending within the tank, and rotatable contact bridges supported by said shafts at different horizontal planes within the tank.

2. A polyphase oil switch comprising a cylindrical tank, a lid therefor, a plurality of shafts spaced lengthwise of and supported by said lid and depending within the tank, and rotatable contact bridges supported by said shafts at different horizontal planes within the tank.

3. A polyphase oil switch comprising a tank, a pair of fixed contacts therein, a shaft of insulating material disposed intermediate the fixed contacts, a metal support carried by the shaft and spaced from the plane of the fixed contacts and a contact bridge carried by said metal support, said bridge being curved to contact with the fixed contacts.

4. A polyphase oil switch comprising a tank, a shaft, means supporting said shaft to permit limited axial movement thereof, a spring to urge the shaft axially in one direction, and a cam device comprising a cam and cam surface on the shaft and on the tank, respectively, engageable at the end of the switch opening movement and so disposed as to shift the shaft axially against the urge of the spring whereby a braking effect is obtained.

In testimony whereof I affix my signature.

FRANZ HOUŠT.
